US0D1105079S

(12) **United States Design Patent** (10) Patent No.: **US D1,105,079 S**
(45) Date of Patent: ** Dec. 9, 2025

(54) **HANDHELD COMPUTER SCANNER**

(71) Applicant: **MEFERI TECHNOLOGIES CO., LTD.**, Chengdu Hi-tech Zone (CN)

(72) Inventor: **Xiaobo Zhao**, Sichuan Pilot Free Trade Zone (CN)

(**) Term: **15 Years**

(21) Appl. No.: **35/520,515**

(22) Filed: **Feb. 26, 2024**

(80) **Hague Agreement Data**

Int. Filing Date: **Feb. 26, 2024**

Int. Reg. No.: **DM/236141**

Int. Reg. Date: **Feb. 26, 2024**

Int. Reg. Pub. Date: **Apr. 12, 2024**
